(57) **CLAIM**

The ornamental design for a hand stop for a firearm as shown and described.

DESCRIPTION

FIG. 1 is an elevated front right side perspective view of the first embodiment of a hand stop for a firearm, showing my new design;

FIG. 2 is an elevated front left side perspective view of the hand stop of FIG. 1.

FIG. 3 is a depressed rear right side view of the hand stop of FIG. 1.

FIG. 4 a front elevational view of the hand stop of FIG. 1.

FIG. 5 is a right side elevational view of the hand stop of FIG. 1, the left side being a mirror image thereof.

FIG. 6 is a top plan view of the hand stop of FIG. 1.

FIG. 7 is a bottom plan view of the hand stop of FIG. 1.

FIG. 8 is a rear elevational view of the hand stop of FIG. 1.

FIG. 9 is another elevated front right side perspective view of the hand stop of FIG. 1, showing the hand stop attached to a firearm, the firearm forming no part of the invention.

FIG. 10 is an elevated front right side perspective view of the second embodiment of a hand stop for a firearm, showing my new design;

FIG. 11 is an elevated front left side perspective view of the hand stop of FIG. 10.

FIG. 12 is a depressed rear right side view of the hand stop of FIG. 10.

FIG. 13 a front elevational view of the hand stop of FIG. 10.

FIG. 14 is a right side elevational view of the hand stop of FIG. 10, the left side being a mirror image thereof.

FIG. 15 is a top plan view of the hand stop of FIG. 10.

FIG. 16 is a bottom plan view of the hand stop of FIG. 10.

FIG. 17 is a rear elevational view of the hand stop of FIG. 10; and,

FIG. 18 is another elevated front right side perspective view of the hand stop of FIG. 10, showing the hand stop attached to a firearm, the firearm forming no part of the invention. The dashed lines in the figures depict portions of the hand stop that form no part of the claimed design. The dashed-dot-dashed lines and greyscale in the figures depict environmental structures that form no part of the invention.
